UNITED STATES PATENT OFFICE.

CHARLES E. BERO, OF CHICAGO, ILLINOIS.

MATTRESS.

1,214,415.

Specification of Letters Patent. Patented Jan. 30, 1917.

Application filed April 26, 1915. Serial No. 23,811.

To all whom it may concern:

Be it known that I, CHARLES E. BERO, a citizen of the United States, and resident of Chicago, in the county of Cook and State 5 of Illinois, have invented certain new and useful Improvements in Mattresses, of which the following is a full, clear, and exact specification.

This invention relates to improvements 10 in mattresses, and also cushion seats in which a series of upright convolute springs have heretofore had their adjacent end coils connected by means of metallic clips or twisted wires, or else have had their wires 15 for its entire length covered by a woven fabric, stitched thereon with their adjacent end coils connected by a wrapping of similarly covered wires in efforts to render the mattress noiseless when in use.

20 The prime object of this invention broadly stated is to utilize the ticking or other textile fabric cover for the springs of a mattress as a means for sustaining the springs in their upright operative position from 25 contact with each other, and to have the end coils of adjacent springs so connected with the cover that the springs are held in an upright position against substantial lateral movement, the one independently of the 30 other.

More specifically stated the object of my 35 invention is to provide a means by which the fabric of the ticking or other textile fabric inclosing the springs may be projected between and prevent the contact of the end coils of adjacent springs, and in such a manner that metallic clips may be passed through the fabric free from contact with the springs for securing the fabric 40 against accidental detachment therefrom.

A further object of my invention is to provide a means by which that portion of the textile cover projected between the springs may be permanently distended and 45 thereby prevented from receding therefrom when locked by a metallic clip, the legs of which are projected through the surface of the cover free from contact with the springs.

50 A further object of my invention is a mattress provided with upright coiled springs connected in such a manner that the weight of the body thereon is distributed as uniformly as may be consistent with its resiliency, and which, however 55 much or violently it may be compressed will be noiseless.

With these ends in view, my invention finds embodiment in certain features of novelty in the construction, combination and arrangement of parts by which the said 60 objects and certain other objects are attained, all as hereinafter fully described with reference to the accompanying drawings, and more particularly pointed out in the claims.

65 In said drawing: Figure 1 is a detail top plan view of a mattress or cushion seat as may be in which my invention finds embodiment. Fig. 2 is an enlarged vertical section therethrough taken on the line 2—2 70 of Fig. 1. Fig. 3 is a similar view of the upper portion of the mattress taken on the line 3—3 of Fig. 1. Fig. 4 is a detail section showing the application of my invention to a stuffed or box mattress, and Fig. 5 75 is a detail section showing a modification in the form and location of the fastening clip.

80 Similar characters of reference indicate the same parts in the several figures of the drawings.

85 Springs 5 are preferably of the hour glass type, but may be of other helical form, and of which there are a number, corresponding with the size of the mattress when arranged as they are with their end coils 90 adjacent each other, which springs are provided with a surrounding cover 6 of tick or other textile fabric, the dimensions of the cover being such that portions thereof between the springs may be crimped to provide folds 7 projecting downwardly between the adjacent end coils of the springs.

95 The springs are secured to the cover, and thereby maintained in their upright position by means of clips 8, the legs of which pass through the cover free from contact with the neck of the coils of the springs, and by their compression against the folds 7, prevent the neck of the fold from spreading apart when the cover is depressed by the weight of the occupant, and the clips from striking contact against the springs confined therein. The cover 6 is stretched 100 tight from edge to edge, both longitudinally and transversely so that the springs, where they pass through clips 8, are forced toward each other and away from the clips. This stretching force is withstood by the fabric, between one clip 8 and the next, but is transmitted from the part of cover 6 over one spring to the part over the adjoining 105 110

springs by the clips 8, so that the folds 7 are not stretched thereby. As the best means for securely locking the folds 7 of the cover to the springs, these folds are distended by means of fibrous ropes 9 passed therethrough, the diameters of which are such that they cannot pass between the adjacent end coils. The ropes 9 instead of being in short pieces for the purposes above described, preferably extend the full length of the mattress so that secured as they are by the clips to the fabric of the cover against endwise movement, they operate to distribute practically over the surface of the mattress the force produced by the occupant from a violent impact of his body against any one of the springs.

While it is true that the folded projections of the cover between the springs produce pockets 10 therein, it should be observed that these pockets are so small as compared with the surface of the cover directly above and over the ends of the springs, that substantially the greater portion of the surface of the cover is normally level, partly filled as are the pockets by the ropes passing therethrough.

For some purposes no supplemental covers need be employed, but for the purposes of a box or stuffed mattress or seat, an outer cover 11 is employed for a stuffing 12, as indicated in Fig. 4, which may be of hair, felt or other materials commonly employed for stuffing mattresses.

35 In Fig. 5 is shown a modification in the form of the fastening clip, the head of which 13, is extended in a straight line against and parallel with the surface of the cover, with its legs 14—14 projecting at a right angle to the head provided with inwardly projected prongs forced through the fabric of the cover into the rope.

In conclusion it should be observed that my invention provides a construction of 45 spring mattress which when once assembled requires no re-adjustment of the tension of the springs for wear and which is not only strong and durable, but noiseless and producible at a maximum cheapness both in 50 cost of material and labor required for its construction.

Having described my invention, what I claim and desire to secure by Letters Patent is:

55 1. A mattress comprising in combination a series of upright helical springs, a woven fabric cover therefor, folds depressed therefrom projecting between and isolating the end coils of adjacent springs from contact with each other, and means spaced from

contact with the end coils of adjacent springs, connecting the surface of the cover with the projecting fold, and maintaining the springs against material lateral movement the one independent of the other. 65

2. A device for the purposes described comprising in combination a series of upright helical springs, the end coils of which are adjacent each other, a ticking or other woven fabric overlying the ends of said springs, folds in said cover projecting between the end coils of adjacent springs, means for distending said folds, and a fastening means projecting through the cover and around the distended fold therein. 70 75

3. A device for the purpose described comprising a series of convolute springs arranged with their end coils adjacent each other, a textile fabric covering therefor provided with folds projecting between the 80 end coils of said springs, a rope for distending said folds and a fastening means for securing the ropes to the fold and preventing a lateral movement of the springs, the one independently of the other. 85

4. A device for the purposes described comprising in combination a series of convolute springs arranged with their end coils adjacent each other, a cover extending over the outer ends of said springs provided with 90 folds projecting between the adjacent end coils thereof, fibrous ropes distending said folds, extending from one edge of the cover to the other, and clips projecting through the surface of the cover and securing the 95 ropes against movement independently of the movement of the springs.

5. A device for the purpose described comprising in combination a series of upright hour glass springs arranged with the end 100 coils of the springs adjacent each other, a fabric extending across and covering the ends of said springs, folds therein projecting between the adjacent end coils of said springs, fibrous ropes crossing each other 105 and extending from edge to edge of said cover, and passing through and distending the projected folds thereof, clip plates passing through the cover and clenched against the surface of the distended folds spaced 110 from contact with the springs and maintaining the springs from a lateral movement independently of each other.

In witness whereof, I have hereunto set my hand and affixed my seal, this 23rd day 115 of April, A. D. 1915.

CHARLES E. BERO. [L. S.]
